UNITED STATES PATENT OFFICE

VINCENT M. VERTUCCI, OF JERSEY CITY, NEW JERSEY

METHOD OF PREPARING CHROMIUM-PLATED FERROUS ARTICLES

No Drawing.

Application filed October 7, 1926. Serial No. 140,219.

The desirable characteristics of electrical-
ly deposited chromium metal are well
known. The chromium coating is extremely
hard and resists abrasion very well; it has
5 a pleasing blue-white color and is capable
of taking and retaining a high polish; it
resists the corrosive action of the atmos-
phere, sea-water, and many acids, including
the common food acids; and it resists oxi-
10 dation even at high temperatures. This
combination of desirable properties renders
it particularly suitable for coating a great
variety of commercial products, and more
particularly articles of iron or steel.

15 Thin, adherent coatings of chromium can
readily be deposited upon clean surfaces of
iron or steel; but investigation has shown
that these coatings as heretofore prepared,
are not continuous over considerable areas,
20 but present defects of the nature of minute
unplated areas, or so-called pin holes, where
the underlying metal is subject to attack.
This difficulty has been partially overcome
in the past by preliminarily coating the
25 iron or steel with copper or nickel, which
may increase the total protective effect, even
though it does not very greatly improve the
continuity of the chromium film.

I have made the surprising discovery that
30 continuous or practically continuous films of
chromium metal may be electrolytically de-
posited directly upon iron, steel or other fer-
rous metal (such as predominantly ferrous
alloy steels) provided the ferrous metal is
35 preliminarily subjected to a suitable heat-
treatment, followed by an adequate clean-
ing of its surface.

Following is a preferred method of carry-
ing out the invention, which is not however
40 limited to the particular manipulations and
operating conditions recited by way of ex-
ample:

The ferrous article to be plated, for ex-
ample in the form of a sheet or if desired of
45 a fashioned implement or article, is first
heated to dull redness, and permitted to cool,
preferably slowly. The surfaces are then
thoroughly cleaned by suitable chemical or
mechanical methods or combinations of
50 these. The cleaning method which I now

prefer is as follows, although it forms no
part of the present invention:

The heat-treated article is immersed in a
hot solution of hydrochloric acid, for ex-
55 ample 20% HCl at 85° C., until all oxid is
removed, after which it is immersed in a
hot solution of caustic soda. The article
is then connected as the cathode in a 10%
solution of sulfuric acid and subjected to a
60 high current density, say 150 amperes per
square foot for five minutes. It is immedi-
ately transferred to a suitable chromi-
plating bath and plated under standard con-
ditions. I prefer to employ a bath consist-
65 ing of an aqueous solution of chromic acid
containing a relatively small proportion of
chromic sulfate, although any other suitable
plating solution may be used.

Articles prepared as above will be found
quite free from pin holes and like defects,
70 even when the chromium coating is extreme-
ly thin, or of the "flash" type. Naturally,
the perfection of the coating is dependent
upon the care with which the several oper-
ations are carried out; and with sufficient
75 care coatings which are absolutely continu-
ous may be applied over large areas. So
far as I am aware, such continuous or prac-
tically continuous coatings of chromium
have not heretofore been secured directly
80 upon ferrous metal surfaces.

I claim:

1. In the art of electrodepositing chro-
mium on iron, steel and predominantly fer-
rous alloys, that improvement which com-
85 prises heating the aforesaid material of fer-
rous character to a dull redness, thereupon
cooling the heated material, and immediate-
ly cleaning the surface of the cool material.

2. In the art of electrodepositing chro-
mium on iron, steel and predominantly fer-
rous alloys that improvement, which com-
90 prises heating the material of ferrous char-
acter to a dull redness, slowly cooling the
heated material, immediately cleaning the
95 cool material with warm dilute hydrochloric
acid until the surface film on said material is
removed, then subjecting said material to the
action of hot caustic soda solution and finally
100 electrolytically cleaning the thus treated ma-

terial in a dilute sulphuric acid medium under the action of an electric current of a character sufficient to give a high current density.

3. The method of electrodepositing continuous platings of chromium on iron, steel and predominantly ferrous alloys, which comprises heating the aforesaid material of ferrous character to a dull redness, thereupon cooling the heated material, and immediately electrodepositing chromium on the freshly cleaned surface of the material whereby a practically continuous plating of chromium is made on the material.

4. The method of electrodepositing continuous platings of chromium on iron, steel and predominantly ferrous alloys, which comprises heating the material of ferrous character to a dull redness, slowly cooling the heated material, immediately cleaning the cool material with warm dilute hydrochloric acid until the surface film on said material is removed, then subjecting said material to the action of hot caustic soda solution, finally electrolytically cleaning the thus treated material in a dilute sulphuric acid medium under the action of an electric current of a character sufficient to give a high current density and immediately thereafter electrodepositing chromium on the freshly cleaned surface of the material whereby a practically continuous plating of chromium is made on the material.

In testimony whereof, I affix my signature.
